(57) **CLAIM**

We claim the ornamental design for a cosmetics brush head with reservoirs, as shown and described.

DESCRIPTION

FIG. 1 is a perspective view of a cosmetics brush head with reservoirs.

FIG. 2 is a left-side elevation view thereof.

FIG. 3 is a right-side elevation view thereof.

FIG. 4 is a front elevation view thereof.

FIG. 5 is a rear elevation view thereof.

FIG. 6 is a top plan view thereof.

FIG. 7 is a bottom plan view thereof.

FIG. 8 is a cross-sectional view thereof taken along line 8-8 in FIG. 6; and,

FIG. 9 is a cross-sectional view thereof taken along line 9-9 in FIG. 6.

Those features shown in broken lines, including a ferrule, shown in FIGS. 1-5 and 7-9, a handle, shown in FIGS. 1-5 and 7-9, and an end of a brush head, shown in FIGS. 1-6, 8, and 9, form no part of the claimed design.
